UPHOLSTERY-MAKING MACHINE AND
METHOD

Allister S. Mitchell, Detroit, Mich., assignor to
National Automotive Fibres, Inc., Detroit,
Mich., a corporation of Delaware

Application August 2, 1933, Serial No. 683,381

30 Claims. (Cl. 112—2)

This invention relates particularly to a machine for and method of manufacturing pleated, stuffed upholstery, such as automobile cushions.

The primary object of the invention is to provide an improved sewing mechanism which is capable of rapid operation and which will produce a cushion which, when stretched laterally, will not tend to open up the seams between the stuffed pleats. In the cushion produced by the improved sewing mechanism, the cushion may be stretched laterally in "hanging" the cushion on the seat, or back, until the lining-fabric becomes taut and lies in a plane surface. This can be done without tending to open the seams between the pleats.

In the accompanying drawings, the invention is shown applied to a multipleater machine of the general construction illustrated and described in my pending United States application No. 572,691, filed November 2, 1931. In general, the present machine operates like the one shown in said application, but sewing mechanisms of improved type are employed.

In a machine of this character, a lining-fabric, a cover-fabric, and batts, or strips of wadding, are fed through the machine. The lining-fabric is continuous. The cover-fabric either is continuous, or pre-cut covers are employed.

Where pre-cut covers are employed, preferably they are automatically positioned upon a bed comprising a pneumatic conveyor and longitudinal ridge-bars extending across the conveyor; and forming-mechanism is employed for pleating the pre-cut covers, seriatim, over the ridge-bars, to form pleats and intervening seam-ridges. The pre-cut covers are successively gripped and carried forward by the conveyor and meet the lining-fabric back of a cross-head, equipped with a forming-roll having circumferential grooves through which the seam-ridges pass. As shown in the application mentioned, the lining-fabric, in passing down under the forming-roll, is drawn over a series of lining-creasers which form seam-positions progressively from the longitudinal center of the machine laterally in both directions.

In accordance with the present invention, each sewing-mechanism is equipped with a hooked sewing-needle and preferably with a cooperating looper-needle, the latter carrying a looper-thread; and the bed of the machine, back of the cross-head, is equipped with a cross-member which supports a plurality of laterally adjustable pleat-entering housings, in which are mounted withdrawable sewing-thread carriers which extend forwardly to the vicinity of the

sewing-mechanisms, the latter being arranged transversely across the machine and disposed in front of the cross-head, upon which the sewing-heads are preferably swingingly mounted.

The sewing-thread carriers, in the preferred arrangement, are in the form of withdrawable longitudinal bars adapted to guide and support the sewing-threads. The front end of each sewing-thread initially engages frictionally a device for holding the end-portion of the thread. The sewing-thread extends across a recess in the thread-carrier, and is adapted to be engaged by a lateral hook with which the sewing-needle is equipped at its piercing end. The sewing-needle works through one thickness of lining and through a U-shaped seam-ridge of the cover-fabric and operates to hook the thread and draw a loop thereof through the fabrics. The looper-needle is mounted so that it will work at the same side of the seam as that from which the sewing-needle enters the seam.

Preferably, a thread-deflector is mounted in the front portion of the sewing-thread carrier and operates to depress the thread and cause it to positively engage the hook of the sewing-needle. The thread-deflector preferably is actuated by a striker carried by the sewing-head, this actuator being preferably independently actuated, but working in timed relation with respect to the movements of the sewing-needle and looper-needle.

The invention is illustrated in a preferred embodiment in the accompanying drawings, which illustrate so much of a multipleater upholstery-making machine of the character shown in the above-mentioned application as is necessary to a complete understanding of the present invention.

In the drawings—

Fig. 1 is a broken vertical sectional view of a multipleater upholstery-making machine embodying the invention, this view showing the relation of one of the sewing-mechanisms and the corresponding sewing-thread carrier to the cross-head of the machine and the means for feeding and forming the fabrics and the means for feeding batts to the pleats as they are formed; Fig. 1^a, a broken detail view illustrating the manner in which the front ends of the ridge-bars are adjustably connected with a cross-member in the bed of the machine near the front end thereof; Fig. 2, a sectional view similar to Fig. 1, on an enlarged scale, omitting certain elements; Fig. 3, a broken longitudinal sectional view showing one of the sewing-thread carriers and its housing, this view being shown on a still larger

scale than in Fig. 2, this section being taken as indicated at line 3 of Fig. 12; Fig. 4, a broken plan view of the front end of one of the sewing-thread carriers, illustrating the manner in which the front end of the thread is initially gripped by the carrier, it being understood that the front end of the thread is withdrawn and passes into the seam when the sewing operation starts; Fig. 4^a, a section taken as indicated at line 4^a of Fig. 4; Fig. 5, a broken vertical sectional view, looking rearwardly, the view being taken as indicated at line 5 of Fig. 1; Fig. 6, a broken vertical sectional view taken as indicated at line 6 of Fig. 2, illustrating a sewing-mechanism; Fig. 7, a sectional view taken as indicated at line 7—7 of Fig. 6; Fig. 8, a broken horizontal sectional view taken as indicated at line 8 of Fig. 7; Fig. 9, a sectional view taken as indicated at line 9—9 of Fig. 1, showing one of the lining-creasers and its relation to one of the sewing-thread carriers and the corresponding ridge-bar; Fig. 10, a section taken as indicated at line 10—10 of Fig. 1; Fig. 11, a transverse sectional view taken as indicated at line 11 of Fig. 13; Fig. 12, a broken plan view, partly in section, showing the front end-portion of a sewing-thread carrier; Fig. 13, a broken elevational view of the device shown in Fig. 12; Fig. 14, a broken vertical sectional view taken as indicated at line 14 of Fig. 12; Fig. 15, a similar view showing the thread-deflector in position to force the thread into engagement with the hook of the sewing-needle; Fig. 16, a transverse vertical sectional view taken as indicated at line 16 of Fig. 14; Fig. 17, a broken longitudinal vertical section taken as indicated at line 17 of Fig. 5 and showing the relation of a looper-needle with respect to the shoe, or seam-plate, of the corresponding sewing-head; Fig. 18, a front end view of one of the sewing-thread carriers; Fig. 19, a broken plan sectional view taken as indicated at line 19 of Fig. 2 and showing the looper needle about to enter a sewing-thread loop; Fig. 20, a similar view showing the hooked sewing-needle about to pass through a looper-thread loop and then to be thrust through the seam for the purpose of drawing a fresh sewing-thread loop through the seam and through the looper-thread loop; Fig. 21, a cross-sectional view of a cushion as it appears before the lining is drawn into a single plane by transverse stretching, the section being taken as indicated at line 21 of Fig. 22; Fig. 21^a, a similar section showing the lining drawn taut by lateral stretch, without opening the seam; and Fig. 22, a broken plan view of a series of cushions before they have been severed from each other.

Describing in detail the preferred embodiment illustrated—

A designates a main frame which is equipped near its front end with a vertically adjustable cross-head A', the frame being provided with a bed-extension A² having longitudinal ridge-bars A³ over which the covers are fed; B, a front suction conveyor mounted in the bed of the machine; C, a series of sewing-mechanisms mounted on the cross-head A' and laterally adjustable thereon to enable the width of the pleats to be varied, said sewing-mechanism being actuated by a common shaft C'; D, D', an upper and lower feed roll by which the upholstery is drawn through the front end of the machine; E, a forming-roll disposed back of and carried by the lower portion of the adjustable cross-head A', said forming roll having spaced circumferential grooves through which the ridge-bars A³ extend; F, a series of

lining-creasers adjustably mounted on a transverse bar F' carried by the bed; G and G', a pair of front batt-feeding rollers; H and H', an auxiliary pair of batt-feeding rolls journaled in supports carried by the main frame, rotation of said auxiliary rolls being periodically arrested to cause severance of the bats; J, forming mechanism adapted to cooperate with the suction conveyor in depressing cover fabrics around the ridges A³ to form seam-ridges and intervening pleat-fullnesses; K, cover fabrics which are fed into the machine; L, lining fabric which is fed down over the lining-creasers F to the forming roll E; and M, bats which are fed by the feed rolls G and G' between the cover and lining fabrics prior to their being sewed by the sewing mechanism C.

It may be remarked here that the sewing-mechanisms employed are, so far as the actuation of the sewing-needle and looper-needle are concerned, quite similar to the sewing-mechanism illustrated and claimed in Ross and Ratley Patent 1,827,694 granted October 13, 1931. However, the member which carries the looper-needle extends across the seam-front of the sewing-head so as to position the looper-needle at the side of the seam, where the sewing-needle is normally located, as will appear from Fig. 5. Also, the sewing-head is equipped with a thread-deflector actuator, as illustrated in Figs. 6—8, this actuator being reciprocated vertically by an independent eccentric on the shaft which works the needles. The manner in which the thread-deflector is actuated will be understood from Figs. 14—15.

Each of the sewing mechanisms C is provided with a supporting bracket 25 which is adjustably secured to the cross-head A' by means of a bolt 26. The head C is shown as comprising a lower cast main section 27 and an upper cast section 28, the two sections forming a divided bearing on the shaft C'; and front and rear bearing-plates 29 and 30, respectively, secured to the front and rear side of the lower portion of the main cast section 27 by means of machine-screws 31. The members 27 and 28 are fastened together by means of machine-screws 32 and enclose a gear 33 which is splined to the shaft C'. The lower main section 27 forms a journal for a shaft 34 on which is keyed a gear 35, meshing with gear 33. Each of the sewing-heads provides a sewing-needle 36 and a looper-needle 37.

As best shown in Fig. 6, the sewing-needle is driven by the shaft 34, whose end portion is equipped with a collar 38 having a crank-pin 39 which drives a connecting rod 40 which is connected to a vertical slide 41 by means of a pivot-pin 42. A screw 36 holds the sewing-needle 36 in the actuating arm 43 whose base portion extends into a hollow portion of the main section and is pivotally connected to said section at 44. The actuating arm is further provided with a pair of trunnions 45 which are engaged by slots 46 in the slide 41.

The looper-needle 37 is also driven from the shaft 34 in the manner described in the above patent. Briefly, the looper-needle actuator comprises a forked-lever 47 (see Figs. 2, 6 and 7), whose upper end portion engages a block 48 which is journaled on an eccentric 49 provided on the shaft 34. The shaft 34 is further provided with an eccentric crank-pin 50 upon which is journaled a connecting rod 51. The lower end of the rod is pivotally connected by a pin 52 to a dove-tail slide 53, held in position by the front and rear bearing-plates 29 and 30 and said pin is journaled in the forked lever. The slide 75

53 acts as a cross-head, keeping the movement of the pin vertical. The looper-needle 31 is carried by an extension arm 54 which is secured to the lower portion of the forked-lever 47 by 5 machine-screws 55.

The thread-deflector actuator, as shown in Figs. 6-8, is also driven from the shaft 34 by an eccentric 60 which drives a ring 61 having a pivotal connection at 62 with a slide 63. Slide 63, 10 like that of a trombone, has two arms 63^a which reciprocate in channels 53^a provided in the slide 53. The lower end portion of the slide 63 is provided with a stud 64 to which is adjustably connected a striker 65, held in position by lock-nut 15 65^a. Thus it will be understood that the striker 65 will reciprocate vertically in timed-relation to the looper-needle and sewing-needle.

The lower end of the main section is provided with a seam-guide plate 66. It will be noted that 20 the looper-needle and sewing-needle both operate on the same side of the guide-plate. A looper-thread 70 is drawn from a suitable source of supply, not shown, about a tensioning device 11, and through a guide 72 carried by one of the 25 screws 31, to the looper-needle. The sewing-threads 75, however, are not threaded through the sewing-needles but are brought into sewing-position within the pleats by means of sewing-thread carriers 76.

30 The sewing-thread carriers 76 are frictionally held in forwardly extending pleat-housings 77 which are adjustably suspended on the lining-creasers F by means of screws 78. The lining-creasers, as shown in Fig. 2, are adjustably secured to the transverse bar F' by means of adjusting bolts 19.

As shown in Figs. 3 and 4, the forward ends of the sewing-thread carriers are bifurcated at 80 and have a cut-away portion at 81 in which the 40 thread-deflectors may operate. The upper front portion of each of the carriers, in advance of the notch 81, is provided with an oblique slot 82 and a small vertically extending resilient finger 83 is set in a narrow kerf cut in the metal below said slot and serving to releasably secure the 45 front end portion of a thread 75 which extends forwardly through the guides 85 provided on the sewing-thread carriers 76. It will be understood that the sewing-thread carriers may be grasped 50 by their handle portion 76^a and withdrawn from the housings to permit the sewing-threads to be attached.

The front end portion of each housing 77 is provided with a stop 86 to limit the forward movement of the thread-carrier within the housing. Also, it is desired to provide a slight vertical adjustment for the front end portion of the thread-carrier. This is accomplished, as shown 55 in Figs. 3 and 11-13, by means of a rotatable member 87 which has an eccentric portion 88 adapted to engage the slot 80 of the thread-carrier. An adjusting screw 89 is provided to releasably hold the eccentric in an adjusted position.

60 The front end of the housing 77 is further provided with a thread-deflector 90 in the form of a bell-crank which is pivotally connected to the housing at 91 adjacent to an opening 92 provided in the housing to register with the notch 65 81 in the thread-carrier. This deflector is best shown in Figs. 12-16. The deflector is provided with a rearwardly and downwardly extending arm 90^a which, when depressed by the actuator 65, will bend the thread 75 around the needle 75 36. The lower arm 90^b of the deflector is urged

rearwardly by a ball 93 which is acted upon by a compression spring 94 adjustably held in position by means of a set-screw 95.

As shown in Figs. 12 and 13, a cloth-guard 96 is attached to the housing 77 and has a cut-away portion 97 through which the sewing-needle may operate. This guard is to prevent any of the material from being drawn out of the housing by the return movement of the needle.

It will be understood that the various mechanisms, for forming and sewing the seam-portions of the fabrics, are laterally adjustable to permit the width of the pleats to be varied. As shown in Fig. 1^a, the longitudinal ridge-bars A³ are fastened to a supporting member 98 by means 10 o° screws 99^a and the supporting member is adjustably secured to the main frame A by means of bolts 99. Also, as shown in Figs. 1 and 5, the vertically adjustable crosshead A' supports divider shoes 100 and 101 which are laterally adjustable by means of bolts 102. The divider shoes serve to press the fabrics down into sewing position as they are advanced by the conveyor B. The front portions of the longitudinal ridge-bars are partially cut away so that the housing 25 11 may be fitted in close proximity thereto, as shown in Figs. 9 and 10. The extreme front portion of the ridge-bars is cut away as indicated at 103 in Fig. 16 to provide a space for the sewing-needle 33. By reference to Fig. 5, it will be 30 understood that the housing members 11 project forwardly into the pleats, between the lining-fabric and associated cover-fabric.

The operation of the sewing mechanism to form a chain-stitch will be understood by referring to Figs. 19 and 20. The sewing-needle 36 is provided near its end portion with a hook 36^a which enables the needle, after piercing a double thickness of the cover-fabric and a single thickness of the lining-fabric, to engage the sewing-thread 75 (with the assistance of the thread-deflector 99) and draw the loop in the sewing-thread to the position shown in Fig. 19. At this time, the looper-needle 31 moves rearwardly and carries the looper-thread 70 through the loop 45 just formed in the sewing-thread. The seam-guide plate 66 is provided with a shallow slot 66^a in which the looper-needle lays the thread 73 just before starting its return movement. The movement of the looper-needle is in the form 50 of an ellipse and an opening is thus formed through which the sewing-needle passes when it next moves to pierce the fabric and again engage and form a loop in the sewing-thread. The looper-thread readily slips out of the groove 66^a 55 as the looper-needle continues its rearward movement and a repetition of these operations provides the chain-stitch illustrated.

In Fig. 21 a cushion is shown in the form it assumes during the sewing operation. Fig. 21^a 60 is a similar section showing the normal condition of the cushion, in use, where the lining is drawn taut by a lateral stretch. It will be seen that there is no tension placed upon the seams of the pleat but that all of the tension is taken up by 65 the lining fabric.

The foregoing detailed description has been given for clearness of understanding only, and no unnecessary limitation should be understood therefrom, but the appended claims should be 70 construed as broadly as permissible, in view of the prior art.

What I regard as new and desire to secure by Letters Patent is:

1. In means of the character set forth: fabric- 75

feeding and forming means; thread-guiding means adapted to lie at one side of a seam and carry a sewing-thread; a hooked sewing-needle operatively mounted to work through the seam 5 from the opposite side and draw a loop of the sewing-thread through the seam and through a looper-thread loop; and an operatively mounted co-acting looper-device serving to carry a looper-thread loop through the drawn sewing-thread 10 loop.

2. Means of the character set forth in claim 1, equipped with means for deflecting the sewing-thread to insure engagement with the hook of the sewing-needle.

15 3. In a machine for manufacturing pleated upholstery; means for feeding fabrics and forming pleats and intervening seam-portions; a plurality of sewing-mechanisms equipped with hooked sewing-needles and cooperating looper-devices; and a plurality of sewing-thread carriers 20 back of the sewing-mechanisms and extending forwardly into the pleats, from which the sewing-needles hook the sewing-threads and draw loops thereof through the seams, whereby chain-stitches may be formed by the loops of the looper-threads and the loops of the sewing-threads. 25

30 4. A machine as specified in claim 3, in which the sewing-thread carriers have associated therewith means for positively deflecting the sewing-threads into engagement with the hooks of the sewing-needles.

35 5. A machine as specified in claim 3 in which the sewing-thread carriers are equipped with thread-deflectors and the sewing-mechanisms are equipped with means for actuating said deflectors.

40 6. A machine as specified in claim 3, in which the sewing-thread carriers are equipped with thread-deflectors and the sewing-mechanisms are equipped with driven devices movable with relation to the sewing-heads for actuating said deflectors.

45 7. In a machine for manufacturing pleated upholstery: means for feeding fabrics and forming pleats and intervening seam-portions; means for feeding batts to the pleats; a plurality of sewing-mechanisms equipped with hooked sewing-needles and cooperating looper-devices; and a plurality of sewing-thread carriers back of the 50 sewing mechanisms and extending forwardly to the pleats, from which the sewing-needles hook the sewing-threads and draw loops thereof through the seams, said looper-devices being positioned to carry looper-thread loops through the sewing-thread loops after the latter have been 55 drawn through the seams.

60 8. A machine as specified in claim 7, in which the sewing mechanisms are mounted on a cross-head beneath which the fabrics pass, and the sewing-thread carriers are mounted on stationary supports back of said cross-head and extend forwardly beneath the cross-head to position to cooperate with the needles of the sewing-mechanisms.

65 9. A machine as specified in claim 7, in which the sewing-mechanisms are carried by a cross-head and the sewing-thread carriers are withdrawably mounted in forwardly extending housings carried by fixed supports disposed back of said cross-head.

70 10. A machine as specified in claim 7, in which the sewing-mechanisms are mounted on a cross-head and the sewing-thread carriers are mounted for lateral adjustability in the rear of said cross-head.

11. A machine as specified in claim 7, in which said sewing-mechanisms are mounted on a cross-head and said sewing-thread carriers are mounted in pleat-housings supported back of the cross-head and disposed beneath lining-creasers located back of the cross-head. 5

12. A machine as specified in claim 7, in which the sewing-mechanisms are mounted on a cross-head and the sewing-thread carriers are mounted in housings forming units with corresponding lining-creases disposed above said housings, said units being mounted to permit them to be adjusted laterally. 10

13. A machine as specified in claim 7, in which the sewing-mechanisms are mounted on a cross-head and the sewing-thread carriers are mounted in pleat-entering supports equipped with movable thread-deflectors, and the sewing-mechanisms are equipped with means for actuating said deflectors. 15

14. A machine as specified in claim 7, in which the sewing-thread carrier is an elongated member equipped with means for guiding a thread longitudinally of said member, said means being recessed at the point where the sewing-needle enters. 20

15. A machine as specified in claim 7, in which the sewing-thread carriers are withdrawably mounted in pleat-entering housings and means are provided for adjusting said sewing-thread carriers with relation to their housings. 30

16. A machine as specified in claim 7, in which the sewing-thread carriers are recessed to permit entry of the sewing-needles and are mounted in pleat-entering housings equipped with movably mounted thread-deflectors. 35

17. In a machine of the character set forth, the combination of a hooked sewing-needle, a unit adapted for cooperation with said hooked sewing-needle, said unit comprising an elongated pleat-entering housing and an elongated stationary sewing-thread carrier withdrawably mounted in said housing. 40

18. Means as specified in claim 17, in which the pleat-entering housing is equipped with a movably mounted thread-deflector. 45

19. Means as specified in claim 17, equipped with means for initially holding the front end of the sewing-thread, and permitting withdrawal thereof. 50

20. In a machine for manufacturing pleated upholstery: a bed equipped with spaced longitudinal ridges and with means for feeding a cover-fabric, said bed permitting the cover-fabric to be formed into pleat-fulnesses and intervening seam-ridges; a cross-head extending across said bed equipped at its front side with a plurality of sewing-mechanisms equipped with hooked sewing-needles; and sewing-thread carriers mounted back of said cross-head and lying adjacent the ridges of said bed, said carriers extending forwardly beneath the cross-head in position to cooperate with said sewing-needles. 55

21. A machine as specified in claim 20, in which the sewing-thread carriers are combined with and withdrawably mounted in longitudinal housings with which the machine is equipped adjacent the ridges of said bed. 65

22. A machine as specified in claim 20, in which the sewing-thread carriers are combined with and mounted in longitudinal housings with which the machine is equipped adjacent the ridges of said bed, and in which divider-shoes are mounted in said machine and overlie said housings and adjacent ridges. 70

23. In an upholstery-making machine: means for feeding fabrics and forming pleats and intervening seam-portions; and sewing-mechanisms for sewing the fabrics together at said seam-portions, the sewing-mechanism comprising a sewing-thread-carrier disposed at one side of the seam, a hook sewing-needle and a cooperating looper-thread-carrying looper-needle mounted at the opposite side of the seam, said needles cooperating to interloop the two threads at that side of the seam where said needles are mounted.
- 10 24. A machine as specified in claim 23, in which the sewing-thread carrier extends into the pleat at the opposite side of the seam.
- 15 25. A machine as specified in claim 23, in which the sewing-thread carrier comprises a longitudinal bar equipped with thread-guides, said bar being cut away at the point where the sewing-needle enters.
- 20 26. A machine as specified in claim 23, combined with a sewing-thread carrier and a housing therefor extending into the pleat, said housing being equipped with a movably mounted thread-deflector, and means associated with the sewing-mechanism for actuating said deflector.
- 25 27. In an upholstery-making machine: means for feeding fabrics and forming pleats and intervening seam-portions; a sewing-thread carrier and a housing therefor extending into the pleat, said housing being equipped with a movably mounted thread-deflector; and sewing-mechanism comprising a head, a sewing-needle slide, a looper-needle slide, and a thread-de-

flector actuator slide confined by channels provided in one of the first-mentioned slides.

28. Mechanism as specified in claim 27, in which all of the slides are actuated by eccentrics on a common shaft.

29. The process of forming pleated upholstery, which comprises: forming fabrics into pleats and intervening seam-portions; holding sewing-threads in longitudinal position within the pleats adjacent the seam-portions; hooking successive portions of the sewing-threads and drawing them as loops through the seam-portions of the fabrics; and forming looper-thread loops in a looper-thread at the outer side of the seam-portion and carrying them through the sewing-threads and carrying the sewing-thread loops through the looper-thread loops.

30. In the manufacture of stuffed pleated upholstery, the steps which comprise: feeding a fabric and forming pleat-fulnesses and intervening seam-portions therein; feeding batts to the pleat-fulnesses; feeding a second fabric into position to cover the pleat-fulnesses; holding sewing-threads within the pleats adjacent the batts; hooking successive portions of the sewing-threads and drawing them as loops through the seam-portions; and forming loops in looper-threads at the outer side of the seam-portions and carrying the looper-thread loops through the sewing-threads and carrying the sewing-thread loops through the looper-thread loops, thus forming an external two-thread chain stitch.

ALLISTER S. MITCHELL.
